Primary Examiner — Randall Gholson(74) Attorney, Agent, or Firm — Maschoff Brennan(57) CLAIM

The ornamental design for a kitchen wrist guard, as shown and described.

DESCRIPTION

FIG. 1 is a top perspective view of the kitchen wrist guard; FIG. 2 is bottom perspective view thereof;

FIG. 3 is a top plan view thereof;

FIG. 4 is a bottom plan view thereof;

FIG. 5 is a right side view thereof, the left side view being a mirror image of the right side view shown;

FIG. 6 is a front view thereof; and,

FIG. 7 is a back view thereof.

The broken lines in the drawings depict environmental subject matter only and form no part of the claimed design.
